CLOSING RING

Arthur H. Van Horn, Rocky River, Ohio, assignor
to Cornell Securities Corporation, Cleveland,
Ohio, a corporation of Delaware

Application January 15, 1941, Serial No. 374,544

3 Claims. (Cl. 220—61)

My invention relates to shipping containers such as metal barrels, drums, pails or the like, and more particularly relates to an improved type of sealing ring for removably securing a cover in place in the open end of the container and in fluid tight sealed relation thereto.

It is one of the objects of the present invention to provide a transversely split sealing ring with means for contracting and expanding the ring about the cover and container by employing a lever or handle pivotally carried by one end of the ring and having means engageable with the other end of the ring so that upon moving the lever in one direction of rotation the ring will be contracted and by moving it in an opposite direction the ring will be expanded.

A further object of the invention is a sealing ring of the above named character in which the only movable part employed in expanding the ring is the lever.

A further object is to construct a sealing ring of the type above described in which the lever is provided with means engageable with a lug on the ring end to expand the ring when the lever is moved in one direction and to contract the ring when the lever is moved in another direction.

Another object of the invention consists in reducing the ring expanding and contracting means to a minimum number of parts thereby reducing the cost of manufacture and assembly without impairing its effectiveness or ease of operation.

Another object of the invention is to provide an operating lever which is positive and direct in its action to open or close the ring, thus making it possible to eliminate connecting links between the lever and the end of the ring opposite that to which the lever is pivotally connected.

Another object consists in the provision of a lever for contracting and expanding the ring in which the lever operates about one fulcrum to contract the ring and about a different fulcrum to expand the ring.

A still further object of the invention is to reduce the required number of movable parts to a single lever to seal effectively and remove a cover from a container without the use of tools.

A further object consists in providing means of the above described character which can be operated outside the container side walls and below the ring and bead of the container, without presenting any objectionable protruding parts which might interfere with nesting or storing of the containers.

Other objects and advantages of the invention will become more apparent from the following description of an embodiment thereof, reference being made to the accompanying drawing in which like reference characters are employed to designate like parts throughout.

In the drawing:

Figure 1 is a top plan view of an embodiment of my invention shown applied in use;

Figure 2 is an enlarged side elevation of the same in the vicinity of the ring ends and shows the ring in contracted sealing position;

Figure 3 is a fragmentary side view of the ring showing the lever in position at the beginning of the ring contracting stroke;

Figure 4 is a similar view illustrating the manner in which the lever is operated about a second fulcrum to expand the ring by forcibly separating the ring ends;

20 Figure 5 is a vertical section taken on line 5—5 of Figure 2; and

Figure 6 is a vertical section taken on line 6—6 of Figure 2.

In the art of shipping and storing containers such as metallic barrels, drums, pails or the like, it is common practice to seal the cover on the open end of the container by means of a contractible sealing ring of channelled cross section carrying mechanism for contracting the ring to seal the cover on the container.

Many of these devices, however, rely upon a plurality of elements to contract or to expand the ring, as for instance, links and levers, racks and pinions, multiple or compound links and lever arrangements and the like.

My invention is designed to reduce the number of elements of such devices to a single movable element which operates both as a ring contracting member and a ring expanding member depending upon its direction of movement. Thus the assembly is simplified in construction and, of course, is more economical to manufacture.

In carrying out the present invention in accordance with the embodiment illustrated in the accompanying drawing, I have shown a metal barrel, drum or pail at 1 which is provided with a bead 2 rolled outwardly at its open end. The cover 3 has a peripheral upwardly and outwardly extending flange 4 which is adapted to overlie the packing 5 and the bead 2 as shown. The channelled, split clamping ring 6 engages the cover flange 4 and the bead 2 and presses the same together against the packing in sealing relation when the ring is contracted.

55 Adjacent one end 7 of the split ring 6, I have

provided a lug or hanger 8 which extends downwardly under the bead and close to the side wall of the container as shown. A lever assembly is pivotally carried by the lug at 9. The other end 10 of the ring carries a rigid member 11 also extending downwardly from the ring and under the bead and in alignment with the central plane of the lug 8.

The lever assembly above referred to, comprises a handle portion 12 and an extension lever arm 13 pivotally connected as a unit within the U-shaped lug 8 by means of the pin 9 and operates as a rigid unit about this fulcrum in one direction for contracting the ring as will be more fully brought out hereinafter. The handle portion of the lever assembly is pivotally carried at 14 within the lever arm 13.

The lever arm 13 may be L-shaped in elevation as shown to permit the use of a short lug 8 and further to locate the fulcrum 9 preferably above the fulcrum 14, although the lug 8 may be extended downwardly so that the fulcrums 9 and 14 will be in substantial alignment. However, the preferred arrangement is that illustrated in the drawing, since the advantages of smoother operation are greater as will be seen as this description progresses.

The outer portion of the lever arm 13 is slotted or bifurcated at 15 to receive an end 16 of the handle 12. An abutment or stop 17 is formed within the slotted end of the lever arm 13, while the adjacent end of the handle 12 is formed with an extension 18 engageable by the stop 17 to prevent movement of the handle relative to the lever arm 13 in a counterclockwise direction from an aligned position as indicated in Figure 2. From this position, however, the handle is freely movable on the lever about the fulcrum 14 in a clockwise position to expand the ring as shown in Figure 4.

In order to effect positive ring expansion and contraction as a result of direct engagement of the rigid handle member with rigid cooperating means carried by one end of the ring, I have provided spaced cams 19 and 20 formed as an integral part of the handle portion of the lever and extending upwardly in the direction of the lower flange of the ring and the bead of the container, and to receive therebetween the tooth or cam member 11 as illustrated in Figure 2.

It will be noted particularly from Figures 2, 3, and 4 that the opposite walls 21 and 22 of the cam 11 are formed for sliding engagement with the crown portion 23 and 24 of the members 19 and 20 respectively. The wall 21 is convexly curved from the root of the member 11 to its lowermost portion, while the wall 22 is substantially vertical from the root to the lowermost portion although it may be merely an inclined wall, or it may be concavely curved.

In use, the embodiment of my invention herein described and shown operates in substantially the following manner.

The expanded ring is applied to a container and cover as illustrated in Figures 3 and 5 so that the ring flanges loosely overlie the cover flange and the bead of the container. To contract the ring and thereby seal the cover on the container, the operator grasps the handle 12 and pulls it upwardly about the fulcrum 9. It will be noted that an upward pull on the handle from the position shown in Figure 3 will cause the whole lever assembly comprising the handle 12 and the arm 13, to move as a rigid lever about the pin 9 because of the fact that the extension

18 at the fulcrumed end of the handle 12 presses against the abutment 17 of the lever arm. Thus movement of the handle 12 in a counterclockwise direction from the position shown in Figure 3 can only result in movement of the lever assembly as a single rigid lever about the fulcrum 9.

As the lever approaches the ring, the crown 23 of the tooth or cam 20 will engage the convex wall of the cam 11 and slide along it until the offset portion 23 snaps into the seat 25. During this movement of the lever the ring ends are pulled toward each other due to the opposed circumferential closing forces applied to one ring end 15 through the lug 8 and to the other ring end through the cam 11. When the ring is fully contracted, the parts will be in the positions indicated in Figure 2 and the lever can be maintained in such position in shipment by means of the snap seating of the offset cam end 23 in the socket or seat 25 of the cam 11. Furthermore the handle may be provided with an apertured tab 26 in alignment with an apertured stop 27 for receiving a sealing wire 28 as a precaution against unauthorized access to the interior of the container.

When it is desired to remove the cover 3 by expanding the ring, the sealing wire 28 is, of course, first removed. The operator then exerts 30 a downward thrust on the handle 12 unseating the offset end 23 from the seat 25. It will be noted that a clockwise movement of the handle 12 from the position illustrated in Figure 2, will be about the fulcrum represented at 14 as shown 35 more clearly in Figure 4, rather than about the fulcrum 9, thus shortening the leverage from the outer end of the handle to the fulcrum 14 as contrasted to the longer leverage from the end of the handle to the fulcrum 9 when the lever is 40 moved in a reverse direction to contract the ring.

It will also be noted that the distance between the fulcrum 9 and the toe 23 of the cam 20 is greater than that between the fulcrum 14 and the crown 24 of the member 19 which engages 45 the surface 22 of the cam 11 during forcible expansion of the ring.

The longest radius of the cam 19 extends in a plane slightly to the right of the vertical when the ring is fully contracted as shown in Figure 2 and 50 is of sufficient length that a clockwise movement of the lever 12 and the cam 19 will cause a spreading of the ring ends 7 and 10 due to sliding engagement of the crown 24 with the wall 22 of the member 11.

55 As the ring end 10 moves to the right in Figure 4 during the expanding operation, the cam 20 will move outwardly and downwardly of the member 11 without interfering with the ring expansion. Ordinarily, only a limited force is required to 60 begin expansion of the ring due to the fact that the ring is normally slightly expanded. It is often necessary to apply an initial force to expand a ring which has become set in its contracted position on the container and the present invention includes means for applying such initial forces 65 through the operation of a lever having portions engageable with an end of the ring.

From the foregoing, it will be observed that the invention provides a simple and compact means 70 for contracting and expanding a sealing ring into and out of cover sealing relation with the container by the operation of a single lever in which the same operates about one fulcrum to contract the ring and about another fulcrum to expand 75 the ring.

I have also provided means for preventing movement of the lever arm 13 about its fulcrum during the expanding operation. Such means may consist of crimping the lug walls vertically inwardly as at 30 and recessing the lever arm at 31 vertically so that the crimp will snap into the recess and thus resist turning movements in the lever arm when it is desired to move the lever handle independently in a clockwise direction to expand the ring as in Figure 4.

The compression of the lug walls 8 to set the crimp 30 in the recess 31 is easily maintained by the beaded pin 9 although this lever arm is capable of being moved to the position shown in Figure 3 to prepare the lever assembly for its function of contracting the ring.

Various changes may be made in the details of construction and arrangement of parts of my invention without departing from the spirit of the same or the scope of the appended claims.

I claim:

1. A clamping ring for sealing a cover on the open end of a receptacle comprising a transversely split channeled ring having portions engageable with the cover and with the receptacle to press the same together when the ring is contracted, members depending from the ring near its respective ends, and means for contracting and expanding the ring, said means including a lever pivotally connected with one of said ring carried members, a handle pivoted to said lever, a stop on said lever engageable with a portion of the handle for movement with the lever in one direction but movable independently of the lever in an opposite direction, and a pair of longitudinally spaced abutments carried by the lever handle to engageably receive therebetween the said other ring carried member whereby upon movement of the lever handle in one direction the ring is contracted.

2. A clamping ring for sealing a cover on the open end of a receptacle comprising a transversely split channeled ring having portions en-

gageable with the cover and with the receptacle to press the same together when the ring is contracted, members depending from the ring near its respective ends, and means for contracting and expanding the ring, said means including a lever pivotally connected with one of said ring carried members, a handle pivoted to said lever, a stop on said lever engageable with a portion of the handle for movement with the lever in one direction but movable independently of the lever in an opposite direction, and a pair of abutments spaced longitudinally of the lever and carried by the lever handle to engageably receive therebetween the said other ring carried member whereby upon movement of the lever handle in one direction the ring is contracted, and upon movement of the lever handle in an opposite direction the ring is expanded.

3. A clamping ring for sealing a cover on the open end of a receptacle comprising a transversely split channeled ring having portions engageable with the cover and with the receptacle to press the same together when the ring is contracted, members depending from the ring near its respective ends, and means for contracting and expanding the ring, said means including a lever pivotally connected with one of said ring carried members, a handle pivoted to said lever for movement with the lever in one direction but movable independently of the lever in an opposite direction, a lateral abutment on said lever handle, said other ring carried member having a convex face engageable by said abutment when the lever handle is moved in one direction to contract the ring, a bearing member on said abutment having bearing engagement with the convex face of the said other ring carried member, said convex face having a retaining seat to receive the bearing member and to retain the lever handle in ring contracted position.

ARTHUR H. VAN HORN.
